UNITED STATES PATENT OFFICE

90,976

DESIGN FOR A HEEL PLATE

William Doering, Muscatine, Iowa

Application July 31, 1933. Serial No. 48,884

Term of patent 14 years

To all whom it may concern:

Be it known that I, WILLIAM DOERING, a citizen of the United States of America, residing at Muscatine, in the county of Muscatine and State of Iowa, have invented a new, original, and ornamental Design for a Heel Plate, of which the following is a specification, reference being had to the accompanying drawing, forming a part thereof.

In the drawing:

Figure 1 is a bottom plan view of a heel plate showing my design.

Figure 2 is a side view of the same.

I claim:

The ornamental design for a heel plate as shown.

WILLIAM DOERING. [L. S.]
